US00D892062S

(12) **United States Design Patent** (10) Patent No.: **US D892,062 S**
Madsen et al. (45) Date of Patent: ** Aug. 4, 2020

(54) **POWER OUTLET COVER**

(71) Applicants: **Melody Ann Madsen**, Albuquerque, NM (US); **Carl Damgren Madsen**, Albuquerque, NM (US)

(72) Inventors: **Melody Ann Madsen**, Albuquerque, NM (US); **Carl Damgren Madsen**, Albuquerque, NM (US)

(73) Assignee: **eSolutions Corporation**, Rio Rancho, NM (US)

(**) Term: **15 Years**

(21) Appl. No.: **29/633,816**

(22) Filed: **Jan. 16, 2018**

(51) LOC (12) Cl. **13-03**

(52) U.S. Cl.

USPC **D13/156**

(57) **CLAIM**

The ornamental design for a power outlet cover, as shown and described.

DESCRIPTION

FIG. 1 is a front perspective view of a first embodiment of a power outlet cover, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an exploded perspective view of the first embodiment with the lid for the power outlet cover removed;

FIG. 9 is a front perspective view of a second embodiment of a power outlet cover, showing our new design;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof; and,

FIG. 16 is an exploded perspective view of the second embodiment with the lid for the power outlet cover removed. The broken lines depict portions of the power outlet cover which form no part of the claimed design.
